UNITED STATES PATENT OFFICE

MARTIN H. O'TOOLE, OF EVERETT, MASSACHUSETTS, ASSIGNOR TO BOSTON RUBBER MAT COMPANY, OF BOSTON, MASSACHUSETTS, A CORPORATION OF MASSACHUSETTS

LINK MAT AND BORDER

Application filed February 11, 1928. Serial No. 253,707.

This invention relates to mats for use on floors and for analogous purposes, composed of links and pintle or hinge rods connecting such links in a continuous fabric of desired dimensions, and to borders for such mats and means for connecting the border to the link fabric, the whole constituting a complete mat. In this specification the term "border" includes one or more edge or border pieces extending, or adapted to extend, along one or more of the edges of the link structure. The term thus includes both a complete frame surrounding and enclosing the entire link fabric, and a partial frame embracing a part only of the fabric, as well as a border piece extending along only one of the sides of the fabric. In the preferred construction the border is of substantially equal thickness or height to the links of the link fabric in the part which adjoins the links, and is beveled thence to a substantially less thickness or height at its outer edge in order that a person stepping upon the mat will be less liable to stub his toe on its edge. Besides this the border gives the mat a finished quality, otherwise lacking.

The invention consists in the combination of a link mat and border, including means for uniting the border to the link fabric, as hereinafter described and pointed out in the claim with reference to the drawings.

In the drawings,—

Fig. 1 is a plan view of a link mat and border embodying the present invention partly broken away and partly shown in section;

Figs. 2 and 3 are fragmentary cross sections on lines 2—2 and 3—3 respectively;

Figs. 4, 5 and 6 are plan views on a smaller scale illustrating various forms in which the mat embodying the present invention may be made;

Figs. 7 and 8 are fragmentary detail plan views, partly broken away and shown in section, illustrating alternative means for connecting the body of the mat and the border.

Like reference characters designate the same parts in all the figures.

The body of the mat is a link fabric composed of a number of links *a*, *a*, arranged in

parallel transverse courses and longitudinal rows, the links in each course separated from one another and overlapping at their ends the ends of the nearest links in both adjacent flanking courses. The ends of the links are 55 perforated and are strung upon longitudinal rods or wires *b*, whereby they are alined and joined together. For the purpose of this specification such rods or wires are designated as hinge pintles. The outer ends of 60 the outer rows of links are likewise threaded upon and alined by end rods *c* which serve also as coupling means for securing the border or border members *d*, *d*, at either or both of these sides of the fabric. 65

Each border or border member *d* is formed with notches *e* wide enough to admit the outer ends of the outermost links, and with intermediate tongues or projections *f* which project between such links and are perforated 70 to receive the rod *c*. The latter is passed through the overlapping tongues *f* and outermost links, and is thus also a pintle connecting the border member to the link fabric. 75

Other border members *g* and *h* are provided to finish the sides of the mat intermediate those to which the members *d* are connected. They are secured in place by connecting means engaging the extremities of the pintles *b*, *b*. One of the means here 80 shown (Figs. 1 and 2) for attaching the member *g* consists of hooks or eyes *j* formed by bending over the protruding ends of the pintles *b* in the plane of the mat, such eyes being passed into recesses, or a continuing 85 longitudinal recess or groove *k* in the border, and there secured by transverse fastenings *l*. The preferred form of one of such fastenings is shown in Fig. 2 and it consists of a screw *l* having a shank adapted to pass through the eye *j* and a head *m* which is embedded in the border member, the shank continuing through the eye and being threaded into a nut *n* likewise embedded in the border. Preferably the screw head and nut 90 and the recess in which they are received are made large enough to insure against cutting or chafing a passageway through to the inner edge of the border, and so releasing it, due to the repeated compression and expansion 95 100

in being walked upon, when made of a resilient material such as rubber composition or a composite structure of fabric and rubber.

The opposite border piece *h* is secured by fastening means of specifically different construction. Here the extended ends of the pintles are provided with eyes *o* in a plane transverse to that of the mat and are entered into disconnected narrow passages or recesses 5 in the piece *h*, and a slender elongated coupling *p* is passed through all of such eyes and through aligned passages in the intermediate substance of the piece *h*. When the border is made of a flexible material, as is 10 preferred, the coupling *p* is a flexible wire cable, of dimensions suited to those of the mat, composed of numerous strands of fine wire. The ends of this cable may be secured by being wrapped around the outer rods *c* and soldered thereto. While the last 15 named securing step is preferably used, it is not essential and may be omitted when the border is provided as an embracing frame, for the overlapping ends of the adjacent parts 20 of such border retain the coupling. Being of flexible and resilient material, the parts of the border adjacent to the ends of the coupling *p* may be forced aside far enough to allow this coupling to be inserted and 25 made fast, after which the material will resume its normal position, conceal and protect the coupling. The use of material having these qualities is necessary when couplings 30 of the character represented by the coupling *p* are used, but is not necessary in connection with fastenings such as the screws or pins *l*. The latter may be put in place even if 35 the border pieces which they secure are wholly rigid. They may be prevented from accidentally 40 working loose by heading or riveting the end of the screw shank over the end of the nut, or upsetting it in the nut so that it will not readily work out.

It will be noted that I have shown the several members of the border as mitered where they adjoin one another. While this is a preferred construction from the point of view of symmetry and finished appearance, it is not essential to the invention, for any one 50 of the members of the border may be extended in undiminished width to the outer edge or edges of the adjacent member or members, the latter then terminating at the inner bound of the member which is thus extended. One, two or more of the border pieces 55 here shown may be used without the others to finish one, two or more edges (less than the whole number) of the mat, leaving the others unfinished, as shown in Figs. 4 and 5, to serve 60 such purposes as the location of the mat in a corner, or snugly against one edge of a threshold, etc.

Still another mode of joining the border members to the link structure is shown in detail 65 in Figs. 7 and 8, and may be assumed

to be embodied in the mats shown in Figs. 4, 5 and 6. In this instance the border pieces which extend parallel to the links are formed with a longitudinal passage *r* wholly surrounded by the material of the border, and 70 openings leading into this passage are formed in the face of the border adjacent to the link structure in alignment with the several pintle or coupling rods. The ends of the latter are 75 extended from the outermost course of links and bent over at right angles to form hooks *b'* far enough distant from the adjacent links to pass through the branch openings and enter the longitudinal passage *r* in the border member, as shown in Figs. 7 and 8. The border, being made of resilient flexible material, is sufficiently flexible to be bent and 80 stretched to the extent required for insertion of the hooked ends of the pintles, and sufficiently resilient to return to its normal dimensions and form, in interlocked relationship with the hooked ends of the pintle rods. This form of connection is simple in the extreme, requiring no parts or members additional to the border and pintle rods themselves, and it is applied and made fast without difficulty. When completed, it is entirely concealed by the unbroken top and bottom 85 faces of the border member.

In order to relieve the border member of 90 chafing and strain by the embedded pintles, the link structure is preferably reinforced adjacent to the border by narrow metal links *s*, the perforations in which closely embrace the pintle rods, and by which the rods are 95 prevented from any side play.

When the mat is provided with a border at one edge only, as shown in Fig. 5, each two adjacent pintle rods may be made of a single wire bent at its middle part to form an integral connecting member *b'*, as shown; but when there are borders at opposite sides, as in Fig. 4, or at three sides, or all the sides, 100 each pintle is made of a separate piece with hooks like the hooks *b'* at both ends. In cases 105 where the border pieces are applied to two adjacent sides of the mat, the endmost pintle rod *c*, which connects the border *d* to the link structure, is likewise formed with a hook *c'*, the bend of which occurs at the mitered junction between the adjacent border members, and the hook portion is entered into the end 110 of the passage *r* in the border *h*.

Any suitable material may be used for the 115 links and border of the mat. All these parts 120 may be made of new vulcanized rubber composition, of one color or of different colors arranged in pleasing design. The use of this material for the border enables the mat to be rolled up on an axis parallel to the pintle rods. But I may cut the links from discarded 125 automobile tires and other rubber fabrics, scraps of sole leather, etc., and make the border pieces also of other materials. These 130 pieces likewise may be made in stock lengths

less than the length or width of the largest mat manufactured, so that a number of them may be adjoined end to end to border one edge of the mat. All such, and numerous other variations, may be made without departure from the invention or from the protection which I claim.

5 What I claim and desire to secure by Letters Patent is:

10 A mat consisting of links and connecting pintles, and a border extending continuously along one edge of the mat beside the endmost course of links, said pintles extending at one end beyond said endmost course of links and being bent to form hooks on their protruding ends, the border having a longitudinal passage between its top and bottom faces and branch openings in such passage extending through the face of the border adjacent to the 15 link structure and in alinement with the several pintles, the pintles extending from the outermost course of links through said branch openings and having bent ends located in said passage.

20 25 In testimony whereof I have affixed my signature.

MARTIN H. O'TOOLE.
